WALTER SCHOENKE, OF LICHTERFELDE, NEAR BERLIN, GERMANY.

APPLIANCE FOR PRACTICING RIDING SPORT.

Application filed October 8, 1925, Serial No. 61,272, and in Germany April 1, 1924.

This invention relates to an appliance for practicing riding sport and consists essentially therein, that legs, which may be spread apart, are being kept in nonspreaded condition by means of one or more springs, at a time when the weight of the rider is not acting upon the appliance by the seating position of the rider while at least one of the said springs is provided so as to act upon the legs at such points, that in inoperative position of the appliance, that is in non-spreaded position of the legs, the lever arm on which said spring is acting will be small. In the operative position of the appliance, that is when the legs are spreaded, the arm of the lever will attain approximately its maximum value. Advantageously the spring is made to have such a preliminary tension, that it keeps not only the appliance in non-spreaded condition against the weights of the animal body and that of the rider, but is in addition to this so strong that it will be enabled to also carry the legs back into their non-spreaded condition during obstacles arising upon the road. The non-spreaded position will be designated in the following as normal position, while the spreaded position of the legs is designated as such.

The action of the afore-mentioned spring exerted in this manner may also be supplemented by pulling means actuated by the stirrup, said means having the tendency in this case to bring the appliance back into its normal position by action of the weight of the rider when imposed upon the stirrup. Especial constructions of the means, which transmit the forces exerted upon the stirrup to the appliance, will be mentioned further below. The same applies to the special means provided according to this invention for bringing the appliance into its normal position, which means may be actuated by the rider by means of the reins.

The weight of the rider which is imposed upon the saddle is utilized according to this invention in an especial manner for bringing the legs into their spreaded position, and more particularly also against a very strong pull of the spring tending to bring the appliance into its normal position. By means of especially provided oblique surfaces, which may also be of curved conformation, there may be attained, that at first the upper ends of the legs will considerably approach each other during imposing the weight of the rider upon the saddle, while the acceleration of the contracting motion may be gradually diminished by properly forming the surfaces which cause said contracting motion. The especial construction of the saddle of the appliance, which is destined to take up the weight of the rider, as well as the connection of these parts with the other parts of the appliance are further features of this invention, and are more fully described as the specification proceeds.

The pressure, which is exerted by the saddle, according to a further feature of this invention, may also be utilized for the purpose of rotating one or both of the rear running wheels during spreading of the legs in the direction of travel. A guiding or steering device, which is actuated by the reins for steering the front running wheel or wheels, as well as an arrangement serving for keeping the steering axis of the front running wheel always more or less in perpendicular position, form also part of this invention. In the specification there are further described some additional features of the invention.

In the drawings an example of a construction according to this invention is shown; in the drawings—

Fig. 1 represents an appliance according to this invention in a side view, partly in section.

Figs. 1^a and 1^b are diagrammatic representations of the condition of the levers forming part of the appliance, said levers being shown in two working positions of the latter.

Fig. 2 is a front leg of the appliance together with the running wheel provided thereon, the steering device according to Fig. 1 being separately represented.

Fig. 2^a represents another position of the leg according to Fig. 2.

Fig. 3 is a top view,

Fig. 4 a front view of the steering device for the front running wheel,

Fig. 5 a top view taken on the rear running axle, and

Fig. 6 shows the connection between the rear legs and several details of the driving mechanism.

In the drawings, 1 designates a front leg, which is pivotally mounted upon a frame 2, said leg acting as a double lever, the frame 2 constituting a carrier therefor. The frame 2 furthermore serves as a carrier for the

rear leg 4, which is pivoted at the point 5 to said frame, said rear leg acting thus as a single lever. The upper end of the front leg 1 is positively connected with the rear leg 4 by means of a connecting rod 8, which is pivotally mounted at the points 6 and 7, so that the motion of the one leg will be transmitted to the other in the manner of a reversed parallelogram. 9 is a spring, which is connected by means of a flexible connecting member 10 by way of a roller 11 mounted upon the frame 2, with the point 6 at the upper part of the front leg. The other end of the spring 9 is connected at the point 12 to a lever 13, while the other end of said lever is pivotally mounted at the point 5; in addition to this the spring 9 at the end 12 thereof is kept under tension by an adjustable tension device 14, which latter at the end opposite to the point of connection with the spring 9 is fastened to the point 7 of the rear leg. By this tension device 14 a strong preliminary tension may be imparted to the spring 9 and enable said spring to be easily inserted. Fastened to the point 6, which is positioned at the upper end of the front leg 1, is a flexible tensioning or pull-transmitting means, such as a string or cable 15, which is carried around a roller 16 mounted on the frame 2 and connected at its other end with the holder or lever 17 for the stirrup. This holder 17 is pivoted at the point of rotation 3 of the front leg to the frame 2. In consequence thereof the point of rotation of the stirrup is positioned very far at the front of the animal body. The part of the holder 17 for the stirrup, which extends from the point 3 towards the rear will thus act as a single armed lever carrying about in its center the point of engagement 15^a of the cable or string 15. A pressure exerted upon the stirrup will therefore very effectively serve to augment the action of the spring 9 in carrying the legs back into their normal position.

As will easily be seen from Figs. 1^a and 1^b the lever action exerted by the spring 9 upon the upper end of the leg will be equal to *a*, that is to say it will have a relatively small value, while the lever action during spreaded condition of the legs will be equal to *b*, that is the said lever action will have a maximum value. It may further be noted, that the legs may be positioned perpendicularly to the animal body, corresponding to their normal or natural position during standing at rest of the animal. For the rear legs the lever arm, by means of which the spring 9 will exert its action, will be equal to *c* and during spreaded position equal to *d*. The value of the lever arm in this case will therefore have been rendered smaller as compared with its value during normal position of the legs. Between the points 12 and 3 there is provided a further spring 18, which in normal position of the legs will be not only devoid of any tension, but in addition to this will have a dead motion at the point 19, said dead motion causing said spring to be tensioned not before the appliance has come into its almost spreaded position. This spring 18 serves to afford a resilient stop for the extreme spreaded position of the legs. Besides this stop there may be arranged a further means for rigidly limiting the motion of the leg, this means serving only as a provision in the event of rupture of one of the springs. This latter means for rigidly limiting the motion of the leg may be constituted by a bolt 20, which is mounted upon the carrier 2, the rear leg resting against said bolt in a recess 21 provided on the former, in case of rupture of one of the springs, whereby the appliance will be protected against further injuries. The effective power of the spring 18 is very strong, for it will act during spreaded position of the legs upon a large lever arm, which is further lengthened during spreading of the legs to assume the value *f*. By this, the decrease of the lever arm *c* of the spring 9 acting upon the lever arm *d* will be more than compensated. To the upper end 6 of the front leg there is pivoted a rod 22, which is firmly connected with a curved part 23, while at the upper end of the rear leg 4 or on the frame 2 there is provided a roller 24, which may freely rotate upon its axle. The saddle, which is designated with the numeral 25, rests upon the rod or frame 22, rollers 26 being interposed between the saddle and the rod. The front part of the saddle is pivotally connected at the point of the front roller 26 with the point of rotation 5 of the rear leg 4 by means of a rod 27. The front roller 26 being positioned during normal position of the appliance above the point 5, the saddle 25 upon lowering of the rod 22, in addition to its vertical motion will be caused to move slightly towards the front. A downward motion of the rod 22 together with its attached curved part 23 will cause a strong tension to be exerted upon the upper end 6 of the front leg 1, since the distance between the point 6 and the point 28, at which the curvature of the part 23 begins, is smaller than the distance between the point 6 and the end 29 of said curvature. The pressure, which is exerted in vertical direction upon the saddle 25, will be able to exert a force for bringing about the spreading of the legs which force is far in excess of the weight of the rider. Connected also with the rod 22 is a rack 30, which is adapted to engage a gear 31 provided at the upper end of the front leg. This gear 31 may be coupled in one direction of rotation with a chain drive 32, 33 and 34, while in the other direction of rotation a no-load device (not

shown) will prevent said chain drive from operating.

The chain-drive 32, 33, 34 will transmit the motion of the gear 31 in one direction upon the shaft 35 of the rear driving wheels 36. The driving wheels 36, again, are mounted upon the shaft 35 in such a manner, that in one direction of rotation they will loosely rotate upon said shaft, while in the other direction of rotation they will be coupled to the latter. This arrangement comprising the rack 30 and the chain-drive 32—34 will have the effect of imparting a rotary motion in the direction of travel to the wheel 36, during spreading of the legs. Connected with the roller 37, which may be driven directly or indirectly by the part 23 or 30, is a string 38, which by interposition of the spring 39 will act upon the tail 40, so that upon forward or reverse motion of this roller, the tail will make upward and downward resilient motion. At the upper end 6 of the front leg there is further provided a tensioning or pull-transmitting means 41, which is guided by the neck 44 pivoted to the frame 2 at the point 42 and connected with the front leg by the link 43. This guiding of the tensioning or pull-transmitting means 41 is effected by the roller 45 provided at the point 42 and by a further roller near the head 47. The head 47 is rotatably mounted at the point 48 on the neck 44. 50 are reins which are carried by way of a roller 51 fastened to the bridle, a further roller 52 and a loosely mounted roller 53, towards the point of rotation 3 of the front leg. A pull which is exerted upon both sides of the reins 50 will cause a backward motion of the lower part of the head 47 by means of the roller 51 which is fastened to the bridle. In this manner a strong pull will be exerted upon the string 41, said pull causing the front leg 1 to be lifted. During raising the appliance from its spreaded into its normal condition, the spring 18, the spring 9, the pressure exerted upon the stirrup and the pull imposed upon the reins will therefore act in the same sense. The front running wheel 54, the same as the rear running wheel 36, is rotatable in the direction of travel, while it will be locked against motion in the opposite sense. During spreading of the legs the front running wheel is rotated, while the rear running wheel is locked against backward rotation. During transit from spreaded position into normal position, the opposite will be the case, viz, the rear wheel will rotate in a direction towards the front wheel, the front wheel being then locked against backward rotation. Displacing the weight of the body of the rider resting upon the stirrup towards the front part of the appliance, which is done by means of the part 17, will have the effect, that the weight of the body rest-

ing upon the stirrup will impose a greater strain upon the front leg than upon the rear leg. In consequence of this displacement of the weight the rear leg may be more easily pulled forward. The heavier strain imposed upon the front leg is not of great importance. The fact, that the point of rotation of the front leg is positioned at a lower point, will cause the lever arm by means of which the pressure imposed will come to effect, to be correspondingly smaller than at the rear leg having its point of rotation more at its upper end. Besides, the front leg at this time will be at standstill and for the purpose of increasing the road friction it must be loaded as much as possible. The roller 53 is mounted in a bearing 55, which at one end is connected to a spring 56 and at the other end with the string 57. This string 57 is carried by way of a roller 58 to a steering lever 59 having the form of two circular segments. The spring 56 is fastened upon the frame 2 at the point 60. A one-sided pull exerted upon the reins 50 will therefore have the effect, that the respective segment 59 will tend to rotate in the direction of said pull. The segments 59 are firmly connected with a steering fork 61 carrying the wheel 54 and being rotatable in a bearing 62. The latter is connected to the upper part of a clip 63, which is pivotally mounted at its lower ends 64 upon the legs 1. The points 64 are thus positioned below the axis of rotation of the running wheel 54 for the purpose of automatically securing a vertical position of the steering fork 61. Rods 66 are pivoted to the clip 63 at the points 65 thereof, said rods at their upper ends being also pivotally connected to the frame 2 at the points 60. The rods 66 will have the effect, that the steering fork 61 will be positively kept in vertical position during every spreaded position of the legs, also in case of a pull being exerted upon the reins. A double-sided pull exerted upon the reins will be compensated by the strings 57 which are of double arrangement, so that in case of a double-sided pull exerted upon the reins 50 there will be no resiliency at the roller 53.

The especial construction for providing a proper bearing surface for the legs at the points of rotation in the frame 2 may be best seen from Fig. 6. The leg 4 is mounted upon the fixed bolt 5 by means of a hub or hollow axle 67. A flange 68 is screwed onto said hub or hollow axle 67, said flange being connected to a second flange 70 by means of screws 69. The leg is now placed between these flanges and will be firmly held in position by the latter. In a similar manner the bolt 7 is provided with a fixed flange 71 and a loose flange 72, which are connected with each other by the screws 73. On the opposite sides of the bolts 5 and

7 a similar bearing is provided for the other rear leg. This way of providing bearings for the rear legs by means of flanges which are mounted upon a long hollow axle or hub 5 will result in strongly re-inforcing the rear legs, especially in case of lateral strains arising during a rotation of the legs. For the front legs bearings are provided, which are similar to those of the rear legs.

13 I claim:—

1. In an appliance for practicing riding sport, the combination of two legs adapted to be alternately spread apart and contracted, one of said legs being mounted as a 15 double lever, a spring for contracting said legs, said spring being associated with means for imparting a preliminary tension thereto, when in position of rest, a flexible connection between one end of said spring and the upper end of the one of said legs, and a guiding means around which said connection is carried, said guiding means being adapted to change the direction of said connection.

25 2. In an appliance for practicing riding sport, the combination of legs adapted to be alternately spread apart and contracted, with a spring for contracting said legs, a flexible connection between said spring and one of said legs, a roller around which said flexible connection is carried, said connection having its points of action on said one leg so positioned, that during spreading of the legs the lever arm on which said spring acts upon the leg will be essentially increased.

3. In an appliance for practicing riding sport, the combination of two legs adapted to be spread apart and contracted, one of 40 said legs being mounted as double lever, a spring for contracting said legs, a flexible connection interposed between said spring and the upper end of the one of said legs, a guiding means, around which said connection is carried, adapted to change the direction of action of said connection, said spring having its point of action so disposed with respect to the leg, that during spreading of the legs the lever arm on which said spring is acting will be essentially increased.

50 4. In an appliance for practicing riding sport, the combination of a front leg, a rear leg, said legs being adapted to be spread apart and contracted, a stirrup, a spring adapted to contract the said legs and in the initial position of the appliance being already tensioned so as to be adapted to keep the said legs in non-spreading condition against the weights of the appliance and of the rider as long as the weight of the rider is exerted through the medium of said stirrup upon the appliance, a seat for the rider, and means for spreading the said legs as soon as the rider sits down on the said seat.

5. In an appliance for practicing riding sport according to claim 4, tensioning means adapted to exert in the initial position of the appliance an essentially greater tension on the said spring than necessary for keeping said legs in non-spreading condition against the weights of the appliance and the rider during inoperative condition of said appliance.

6. In an appliance for practicing riding 75 sport according to claim 4, means for tensioning the said spring and regulating the tension of it.

7. In an appliance for practicing riding sport, a first spring, a leg adapted to be inclined by the weight of the rider and to be returned by means of the said spring, a stop adapted to limit the degree of inclination of the leg, and a second spring being only effective after a certain inclination of the said leg and adapted to positively prevent the said leg from arriving at the said stop while the said springs are intact.

8. In an appliance for practicing riding sport according to claim 7, two legs and 90 stops, and a common second spring for preventing the legs from arriving at their respective stops while the springs are intact.

9. In an appliance for practicing riding sport, a first leg mounted as a double lever, a 95 second leg mounted as a single lever, said legs being adapted to be spread apart and contracted, a spring having tensioning means associated therewith for providing a preliminary tension during inoperative condition of said spring, a flexible connection interposed between one end of said spring and the upper end of said first-mentioned leg, a guiding means around which said connection is carried, and adapted to change the 100 direction of action of said connection, and a second spring adapted to be tensioned during spreading of said legs, both of said springs being further arranged so that the one end of said second spring and the other end of said first spring are positioned below the point of rotation of said second leg, in a manner that the lever arm for the said end of the said second spring will increase in proportion to the decrease of the lever arm 105 for said second end of said first spring during spreading of said legs.

10. An appliance for practicing riding sport according to claim 9, having the first spring adapted to have a dead motion prior 110 to its being tensioned.

11. In an appliance for practicing riding sport according to claim 4, a first of the said legs being mounted as a double lever, and a second leg mounted as a single lever, a flexible connecting member interposed between the one end of said spring and the upper end of said first-mentioned leg, a guiding means around which said connecting member is carried, whereby the direction of action 115

- of said connecting member will be changed, and a second spring which in normal position of the appliance is inoperative and which is being tensioned during spreading 5 of said legs, said second spring being fastened with its free end to said second leg at the point of action of said first spring and with its other end in proximity to the point of rotation of said first leg.
- 10 12. In an appliance for practicing riding sport, the combination of a front leg mounted as a double lever, and a rear leg, said legs being adapted to be spread apart and contracted, a movably mounted neck, a head 15 mounted movably on said neck, a pull-transmitting means inserted between said front leg and said head and carried by said neck, a holding means also carried by said neck, and reins having their point of action at the 20 front part of said head, said pull-transmitting means being so arranged with respect to said head said neck and said front leg, that upon a pull which is exerted on said reins said head will exert by means of said 25 pull-transmitting means a strong pull upon the upper end of said front leg.
13. In an appliance for practicing riding sport, the combination of a front leg, a rear leg, said legs being adapted to be spread and contracted, a support adapted to carry the 30 weight of the rider in seated position, and associated with said legs means adapted to act upon said legs during action of said weight upon said support in a manner that 35 the upper ends of said legs will tend to approach each other.
14. In an appliance for practicing riding sport, the combination of two legs adapted to be spread and contracted in alternation, a frame 40 on which said legs are rotatably supported, the one of said legs being mounted on its upper end as a single lever upon said frame, the other of said legs being mounted on said frame as a double lever at a point 45 at some distance from the upper end of said leg, a support for carrying the weight of the rider in seated position, and a device associated with said support, said device being adapted to move the upper end of said other 50 leg towards the point of rotation of said first leg during a pressure exerted upon said support.
15. In an appliance for practicing riding sport, the combination of two legs adapted 55 to be alternately spread and contracted, a frame on which said legs are rotatably mounted, one of said legs being mounted as a single lever at its upper end on said frame and the other of said legs being 60 mounted at a point somewhat distanced from the upper end, that is as a double lever, on said frame, a saddle, a spring adapted to keep said legs in non-spread condition in opposition to the weight of the appliance 65 and the weight of the rider when not rest- ing upon said saddle, and means associated with said saddle, said means being adapted to move the upper end of said other leg towards the point of rotation of said one leg against the tension of said spring during action of the weight of the rider upon 70 said saddle.
16. In an appliance for practicing riding sport, the combination of a front leg, a rear leg, said legs being adapted to be spread apart and contracted in alternation, a saddle, a member associated with said saddle, said member being immovably mounted with respect to the upper end of said front leg in longitudinal direction thereof 75 and being constructed at its rear end in a manner to cause the upper end of said front leg to approach the upper end of said rear leg during a load which is imposed upon 80 said saddle.
17. In an appliance for practicing riding sport, the combination of a front leg, a rear leg, said legs being adapted to be spread and contracted in alternation, a saddle, and a member associated with said saddle and 85 rotatably mounted at the upper end of said front leg, the rear end of said member being constructed to cause the upper ends of said front and said rear legs to approach 90 each other.
18. In an appliance for practicing riding sport, the combination of two legs adapted to be spread apart and contracted in alternation, a roller connected to the upper end of one of said legs, a saddle, and a member associated with said saddle, said member being immovable with respect to the upper end of the other of said legs in longitudinal direction thereof and being constructed at its rear end in a manner that 95 it will cause the upper end of said one leg to approach the upper end of the said other leg by action on the said roller.
19. In an appliance for practicing riding sport, the combination of two legs adapted 100 to be spread apart and contracted in alternation, and a member, one end of which is immovably mounted with respect to the longitudinal direction of one of said legs and the other end of which is so constructed 105 that while the rider sits on the appliance it will approach the upper ends of said legs first with a greater and thereupon with a smaller force.
20. An appliance for practicing riding 110 sport according to claim 17, having a connecting member interposed between the upper end of the rear leg and the front end of the saddle.
21. An appliance for practicing riding 115 sport according to claim 17 having a connecting member interposed between the upper end of the rear leg and the front end of the saddle, and rollers interposed between the under side of the saddle and a connect- 120
- 125
- 130

- ing member rotatably mounted at the upper end of the front leg.
22. In an appliance for practicing riding sport, the combination of a front leg, a rear leg, said legs being adapted to be spread apart and contracted in alternation, a running wheel mounted upon either of said legs and adapted to rest upon the road, said running wheels being provided with an attachment permitting the rotation of said wheels only in one direction of rotation and adapted to lock said wheels against rotation in the other direction, a saddle mounted to be actuated by the weight of the rider, and means provided at the upper end of said rear leg and adapted to be actuated by said saddle and to transmit its motion positively upon said wheel which is provided on the rear leg.
23. In an appliance for practicing riding sport, the combination of a front leg, a rear leg, said legs being adapted to be spread apart and contracted in alternation, a running wheel mounted on either of said legs, said running wheels having locking means permitting a rotation of said wheels in only one direction, a saddle mounted to permit actuation thereof by the weight of the rider when being seated upon said saddle, and means provided at the upper end of said rear leg and operable in only one direction when actuated by said saddle, said means serving for transmitting the motion upon said saddle upon said running wheel on said rear leg in the direction of travel.
24. In an appliance for practicing riding sport, the combination of a front leg, a rear leg, said legs being adapted to be spread and contracted in alternation, a running wheel on either of said legs which is locked in one direction of rotation and free to rotate in the other direction, a saddle mounted to permit actuation thereof by the weight of the rider when being seated on said saddle, a rack provided at the upper end of said rear leg, and a gear mounted at the upper end of said rear leg to co-operate with said rack, said rack and said gear being in operative connection with said saddle to be actuated by the motion of the latter and adapted to transmit the motion from said saddle to said wheel on said rear leg in the direction of travel.
25. An appliance according to claim 24, having a chain-wheel drive interposed between the gear mounted at the upper end of the rear leg and the wheel mounted on the rear leg, for transmitting the motion from the said gear to said wheel.
26. In an appliance for practicing riding sport, the combination of a front leg and a rear leg, said legs being mounted to permit an alternating spreading and contracting thereof, a running wheel mounted at the under part of said legs and resting upon the road, means associated with either running wheel for locking the latter in one direction of rotation while permitting rotation in the other direction, a saddle movably mounted to permit depression thereof by the weight of the rider when resting upon said saddle, and a rack and a gear in operative connection therewith, both being mounted upon the upper end of said rear leg and in operative connection with said saddle for positively transmitting the motion of the latter to the running wheel on said rear leg in the direction of travel.
27. In an appliance for practicing riding sport, the combination of a front leg pivotally mounted at its upper end to constitute a single lever, a rear leg also pivotally mounted, said legs thus permitting a spreading and contracting motion, a stirrup, an actuating lever operatively connected with said stirrup and pivoted at a point which is at an essential distance from the plane of pressure, which may be exerted upon said stirrup by the rider, and positioned essentially at the front end of the appliance, and pull-transmitting means interposed between said actuating lever and the upper end of said front leg, said pull-transmitting means serving to transmit a pressure exerted upon said stirrup in form of a pull upon said front leg, said pull effecting a tendency of said front leg to move from spreaded into normal position.
28. An appliance for practicing riding sport according to claim 27, having the pull-transmitting means arranged in a manner to have its point of action upon the front leg positioned on the side of the latter which is in opposition to the stirrup.
29. In an appliance for practicing riding sport, the combination of a carrier, two legs pivotally mounted upon said carrier, an axle fixed upon said carrier in the manner of a fixed bolt and serving for providing connection between said legs, a hub mounted upon said axle, a flange firmly mounted upon said hub, a loosely mounted flange provided upon said hub, and connecting means interposed between said firmly mounted flange and said loosely mounted flange for keeping the leg in position.
30. In an appliance for practicing riding sport, the combination of a carrier, legs pivotally mounted upon said carrier, an axle in the form of a fixed bolt connected with said carrier for providing a connection between the legs, a hub mounted upon said axle, two flanges fixed upon said hub, a loose flange mounted on either end of said hub, and connecting means interposed between said loose flange and said fixed flange for keeping said leg in position.
31. In an appliance for practicing riding sport, the combination of a front leg mounted in the form of a double lever, and a rear

- leg, said legs permitting alternate spreading and contracting, a stirrup, a lever operatively connected with said stirrup and pivotally mounted at a point which is essentially at a distance from the plane of action of said stirrup, a flexible pull-transmitting element interposed between said lever and the upper end of said front leg, and a guiding means around which said flexible element is carried and which is adapted to change the direction of action of said flexible element, said flexible pull-transmitting element being connected to said front leg and to said stirrup at such points, that a pressure exerted upon said stirrup will be transmitted as a pull of increased strength exerted upon the upper end of said front leg. 5
32. In an appliance for practicing riding sport, the combination of a front leg, a rear leg, said legs being mounted to permit a spreading and contracting motion, a guidable wheel mounted upon said front leg, a wheel holder swingingly mounted on a horizontal axis, said holder being mounted with respect to said leg at a point which is positioned below the axis of rotation of said wheel. 20
33. In an appliance for practicing riding sport, the combination of a front leg, a rear leg, said legs being mounted to permit a spreading and contracting motion, a steerable running wheel mounted on said front leg, a holder for said wheel mounted swingingly around a horizontal axis, a carrier for said legs, and a connection between said holder and said carrier, said connection being adapted to keep the axis around which said wheel may be rotated during steering essentially in a vertical position during a spreading motion of said legs. 30
34. An appliance for practicing riding sport according to claim 33, having a connection between the wheel, the holder and the carrier, said connection being essentially of parallelogram conformation. 40
35. In an appliance for practicing riding sport, the combination of a front leg, a rear leg, said legs being mounted to permit a spreading and contracting motion, reins, a running wheel mounted on said front leg, a steering device connected to said running 50
- wheel and adapted to steer the latter and a connection between said reins and said steering device for transmitting a pull exerted upon one side of said reins to said steering device. 55
36. An appliance according to claim 35, having a flexible connection between the reins and the steering device for the running wheel. 60
37. In an appliance for practicing riding sport, the combination of a front leg, a rear leg, said legs being mounted to permit a spreading and contracting motion, reins, a running wheel mounted upon said front leg, a steering device for said running wheel, a flexible pull-transmitting means connected to said steering device, a roller provided at the end of said pull-transmitting means, and a guide for said reins, permitting said roller 70 to run loosely upon said reins. 65
38. In an appliance for practicing riding sport, the combination of a front leg, a rear leg, said legs being mounted to permit a spreading and contracting motion, reins, a running wheel mounted upon said front leg, a steering device connected to said running wheel, a flexible pull-transmitting means connected with said steering device and adapted to be actuated by said reins, and a spring connected to the end of said pull-transmitting means for keeping said means in condition of tension. 75
39. In an appliance for practicing riding sport the combination of a leg pivotally mounted in the form of a double lever, a second leg pivotally mounted in the form of a single lever, said legs thus permitting a spreading and contracting motion, a roller mounted at the upper end of said second leg, and a device mounted at the upper end of said first-mentioned leg and operatively connected with said roller, said device being adapted to be actuated by the weight of the rider when in seated position and further arranged in a manner, that upon imposing a load upon said device the component force will essentially act in an angle of ninety degrees at the upper end of said first-mentioned leg. 80 90 95

In testimony whereof I affix my signature.
